(57) **CLAIM**

The ornamental design for a sanding glove, as shown and described.

DESCRIPTION

FIG. 1 is a front perspective view of my invention for a sanding glove.

FIG. 2 is a rear view of the present invention; and

FIG. 3 is a front view of the present invention; and

FIG. 4 is a right side view of the present invention; and,

FIG. 5 is a left side view of the present invention.

1 Claim, 3 Drawing Sheets

FIG. 1

FIG. 2

FIG. 3

FIG. 4

FIG. 5
